strength to resist the strains. They and their attachments will prefer steel.

The tie-bars 40 41 may be formed with the forked ends 36 37 or attached to by rivets or bolts, as may be preferred.

The frog-rail 19 will preferably be of an ordinary rail of the same size as the other rails with which it is to be used, and with the ends convex, as before mentioned, and with a perforation for the end 20; but this portion of the device will be formed of a special section of rail referred to.

15 The whole device is very simple and easily constructed and installed, and of being formed to operate with certain precision, so that the chances for its operation will be eliminated entirely.

20 The lengths of the levers will be so arranged as to bring the ribs 32 33 and 38 39 at a distance from the rail 19 to avoid a collision with the wheels after acting on the device, so as to reach the space between the rails 12 15 before the frog-rail 19 has been actuated.

25 The proportions may be modified to correspond to the conditions of the road or other circumstances under which the device is to be employed, as the device is adapted to all the varying conditions of rail construction.

The device is operative entirely by the lever principle and no springs are required for the construction. This is an important feature of the invention, as springs are liable to become weakened by constant use and refuse to act at some critical moment. With this device, however, the levers are always in position for action and, before stated, operate with precision and certainty when required.

The device is entirely independent of the switch-operating mechanism and will not be affected by any improper operation of the switch mechanism or by any negligence of switchmen or trainmen and requires no attention from the operatives, as it is automatic. The device will not require attention from operatives further than occasional inspection in the same manner as other parts in the main line, but will require no further attention than the inspection.

55 Where the levers 26 27 or any of their attachments come in contact with the ties, wear-plates of suitable metal will be employed between the lever and the ties, and these plates may be arranged in any suitable manner and modified to adapt the device to the different details of construction which may be met with.

Having thus described the invention, I claim is—
